UNITED STATES PATENT OFFICE

FREDERICK J. RAYFIELD, OF CHICAGO, ILLINOIS, ASSIGNOR TO CHAMPION PNEUMATIC MACHINERY COMPANY, OF CHICAGO, ILLINOIS, A CORPORATION OF ILLINOIS

FAN STRUCTURE

Application filed November 15, 1929. Serial No. 407,385.

My invention relates to fan structures particularly adaptable for association with compressors for cooling the compression cylinders thereof.

5 An important object of the invention is to provide a fan structure which can be mounted on the crank shaft of the compressor and which has vane surfaces localized and positioned to project large volumes of air toward 10 the compressor cylinders for keeping them cool.

A further object of the invention is to provide a combined fan and fly-wheel structure comprising spokes and a rim, with the spokes 15 widened out at their ends and having the proper angle or curvature to propel large volumes of air and to localize the air where cooling is desired. Where the structure is mounted on the crank shaft of a compressor 20 having radiating cylinder structures thereon, the vane surfaces will be opposite the cylinders so that the projected air will be localized and concentrated on the cylinders to effect cooling thereof.

25 A further object is to adapt the combined fly-wheel and fan structure for receiving a driving belt for driving the apparatus with which the structure is associated.

Referring to the drawings:

30 Figure 1 is a side elevation of a compressor structure showing my improved fan fly-wheel mounted on the crank shaft thereof;

Figure 2 is a side elevation of the fan fly-wheel structure; and

35 Figure 3 is an enlarged section on plane III—III of Figure 2.

As shown, the fan fly-wheel structure comprises a hub 10 from which radiate spokes

40 The hub may be split as shown and provided with flanges 13 by means of which it may frictionally clamp a shaft on which the structure is mounted. The hub may also have a keyway 14, whereby it may be more securely

45 applied to a shaft by means of a suitable key.

As shown in Figure 1, the structure is applied to the crank shaft 15 of a compressor structure C and a key 14' on the shaft will engage in the keyway 14 of the structure. The compressor shown may have one or more 50 cylinders 16 extending radially and which it is desired to cool. The cylinders may have radiator fins or flanges 17 thereon for presenting extensive cooling area.

The spokes of the fan fly-wheel structure 55 are extended or widened and given the proper angle or curvatures to produce large and extensive vane surfaces. Where the fan fly-wheel structure is used in connection with a device such as the compressor structure described, it is desirable and more efficient to 60 localize the vane surfaces so that practically all of the air propelled by the structure will be directed to the cylinders. I, therefore, expand and extend the spokes at their outer 65 ends to form the vane sections 18 to be opposite the cylinders which are to be cooled when the fan device is rotated. The localized vane sections extend diagonally across the rim 12 at the proper angle or curvature for the efficient 70 propulsion and projection of air. By having the expanded vane sections at the other ends of the spokes, the center of gravity of the spokes is moved outwardly toward the rim 12 and the weight of the expanded 75 vane sections added to that of the rim will greatly increase the fly-wheel efficiency.

The rim 12 may be crowned as shown in Figure 1 to receive a driving belt, so that the structure, besides acting as a fan and a fly-wheel, may also function as a driving pulley 80 for the compressor.

Modifications in the structure and arrangement can be made without departing from the spirit and scope of the invention, and I, 85 therefore, do not desire to be limited except as will be necessitated by the prior art.

I claim as follows:

A combined flywheel and fan comprising 90 a hub, a rim, flat spokes radiating from said

hub to said rim, said spokes being entirely within the side planes of said rim and being in planes at diagonals with said hub and rim, the outer sections of said spokes for a distance radially inwardly from their outer ends being of a width to extend from side to side of said rim to form vanes, said spokes at their inner ends extending only a short distance along said hub from one end thereof and gradually expanding in width to the outer sections.

In testimony whereof I have hereunto subscribed my name at Chicago, Cook County, Illinois.

15 FREDERICK J. RAYFIELD.
